UNITED STATES PATENT OFFICE.

CLINTON O. HARRINGTON, OF CHICAGO, ILLINOIS, ASSIGNOR TO ALDOBILT COMPANY, OF CHICAGO, ILLINOIS, A CORPORATION OF ILLINOIS.

MULTIPLE BOND FOR SIGNAL-SERVICE TRACK-CIRCUIT RAILS.

Application filed September 24, 1920. Serial No. 412,540.

To all whom it may concern:

Be it known that I, CLINTON O. HARRINGTON, a citizen of the United States, and a resident of Chicago, in the county of Cook and State of Illinois, have invented certain new and useful Improvements in Multiple Bonds for Signal-Service Track-Circuit Rails, of which the following is a specification.

10 My invention relates to multiple bonds for signal-service-track-circuit rails.

In railroad practice it is frequently desired to utilize the track rails to form an electric circuit for operating track signals at a distant point. For various reasons it is highly desirable that the abutting ends of the rails be connected together by bonds of low electrical resistance. For many years the ordinary practice has been to provide 20 a moderately low resistance bond at the signal-service-track rail joints—one which has a resistance deemed about low enough for practical purposes, but which would be made of much lower resistance were it 25 not for the increase of objections incident thereto. That form of connection consists in bonding two solid copper wires at their ends to the respective end portions of the abutting track rails, the wires extending 30 from end to end and beyond the ends of the fish plate, and is the only form of multiple bonding for signal-service-track-circuit rails of which I am aware. Such bonding has the important advantages of easy 35 inspection and repair; but it has the important disadvantages of relatively high cost, notable susceptibility to breakage at the points of bonding to the rail, marked susceptibility to breakage by misdirected blows 40 of the spike-maul, tamping tools, etc., of the track workman, a strong inducement offered for theft of the valuable copper, which inducement is heightened by the simplicity of its removal by means of 45 clippers, and, in addition, such a bond does not provide the desired low resistance, but only so low a resistance as is obtainable in that way within reasonable costs.

In electric railway practice, where the 50 rails are bonded together to form a circuit for the high tension current used for operating the cars it has been found feasible

to provide a relatively short bond of low electrical resistance, usually of strands of copper wires in cable form, with the ends 55 of the bond connected to the rails quite close to their abutting ends and located under the fish plate, the ends of the conductor being secured to the rails respectively by a welding operation or by wedging pins. In 60 railway signal-track circuits, however, the practice of placing such a short low-resistance bond under the fish plate has not obtained, for the safety of property and life in railway traffic depends so strongly upon 65 the integrity of the signal system that the possibility of constant inspection of the bonds and their ready repair when damaged or broken is a paramount consideration and has, prior to my invention, prohibited the use of the short low-resistance bond located out of sight and out of ready accessibility, as beneath the fish plate. 70

In view of the monetary value of copper, its conductivity, and the comparative ease 75 with which it may be broken, the location of a short low-resistance copper bond where it is safe from all attack, intentional or otherwise, as between the fish plate and the web of the rail, is substantially ideal. 80

Owing to the hitherto considered impracticability of locating such a bond behind the fish plate in railway signal practice it has been suggested to employ the same kind of a short low resistance copper bond provided with terminal pieces which are welded upon the sides of the rail heads near the joint. While this form of bond gives the desired low resistance it is subject to the important objections of requiring the use of a considerable amount of special apparatus and equipment in the field both for the original installation and from time to time in replacing the bonds which become broken, and such bonds are highly susceptible to 90 breakage due to their location near the top of the rail where they are readily struck by downhanging parts of passing trains. Another objection is in the fact that the downhanging loop of conductor overlies the 95 fish plate and interferes with the removal of the fish plate and when the fish plate is removed the conductor is likely to be bent.

Furthermore, owing to its exposed position 100

the conductor must be made considerably heavier than is necessary for the electrical purposes involved, and, also, the value of the bond as scrap copper and its easy removability by unauthorized persons renders the system highly subject to failure on account of theft.

My present invention has for its objects the avoidance of the difficulties, dangers, insufficiencies and expenses inherent in the prior methods as hereinabove pointed out, and this is accomplished through the provision of a low-resistance bond comprising a relatively short conductor electrically bonded to the abutting end portions of the rails and located at a substantially inaccessible place, as between the fish plate and the web of the rail, together with an auxiliary bond, at least the connections of which to the rails are outside the fish plate and where the connections can be readily inspected and repaired; which auxiliary conductor may be of low-grade and substantially inexpensive wire such as iron, the auxiliary conductor being bonded to the rails preferably near the ends of the fish plate. Through these provisions the continuity of the service is bound to be maintained under all of the ordinary conditions of use.

In the accompanying drawings, which form a part of this specification, Figure 1 is a fragmentary face view of two abutting track rails constituting part of the signal circuit, with the fish plate at the rail joint broken away to show the otherwise concealed bond; and Fig. 2 is a vertical cross section as on the line 2-2 of Fig. 1.

The rails 10 and 11, the fish plate 12 and the bolts 13 may be according to well-known construction. The low resistance bond 14 is shown as a short section of stranded wire, preferably copper, and may consist of 20 or 30 strands and have a total diameter of three-sixteenths of an inch. The ends of the conductor 14 are shown as being secured to plugs or wedging pins 15, as by brazing or soldering, a side view of one pin being in Fig. 2. The plugs 15 are frictionally driven tightly into holes in the web of the rail, making electrical connection therewith. The bond between the conductor 14 and the rail may be according to any approved form.

The auxiliary or safety conductor 16 may be considered to be a section of ordinary iron wire, say five thirty-seconds of an inch in diameter. It is electrically bonded to the rail by wedging pin 17 at one end and 18 at the other end, the wire 16 being preferably soldered to the pin, the form of bond shown at 17 and 18 being the same as that shown at 15. In this instance also the conductor 16 may be electrically bonded to the rail in any approved way.

From this construction and arrangement

it is clear that the track-walker or maintainer of the system may readily detect any defect in the bonding of the auxiliary or safety conductor 16 and, with the small tools usually carried for the purpose, the auxiliary bond, if broken, may be restored. The chief interest of the maintainer of the system from time to time therefore is to see that the auxiliary bond is intact, for so long as the auxiliary or safety bond is sound there will be no failure of the system. Although the bond 16 has a relatively high resistance, yet the occurrence of as many as twenty such high resistance bonds operating severally alone at as many joints in the circuit at a time when at the other large number of joints in the track the low-resistance bonds are in operation would not materially affect the satisfactory operation of the signals.

Furthermore, owing to the secluded position of the low-resistance bond 14 and the protection afforded it by the rail and fish plate the danger of its breakage or other failure is reduced to the minimum and failures of this bond would occur but seldom and to only a limited numerical extent between one complete inspection and another, say once a year.

Without the auxiliary bond the placing of the low-resistance conductor in a concealed place such as behind the fish plate would be fraught with much danger, for in case of the failure of one such bond out of say three hundred in the circuit the signal would in all likelihood fail. To locate the particular bond broken would require an inspection with an instrument of each joint until the broken one is found, and then the oftentimes very difficult operation of removing the fish plate would have to be resorted to before the circuit could be restored, all involving much expense and seriously interfering with the use of the track for a considerable period of time. According to these improvements all such danger is avoided, the safety bond, when broken, can be readily discovered and repaired, and repairs to any of the low-resistance bonds may be made at any convenient time.

Inasmuch as the iron wire 16 would seldom if ever be broken except at the connections of it to the rails, this wire may also lie for the most part under the fish plate or be otherwise concealed, but it is essential that at least the connections thereof to the rails be open and readily to be inspected and repaired.

I contemplate also as being within my invention such variations and departures from what is specifically illustrated and described as are included in the scope of the appended claim.

I claim:

The combination of two signal service

track rails abutting each other end to end, a fish plate and bolts holding the rails together, a relatively short low electrical resistance conductor electrically bonded to each rail near the abutting ends thereof and located at a relatively difficultly accessible part of the rails respectively and protec- tively covered by the rail parts, and an auxiliary conductor having its end portions electrically bonded to the rails respectively at places respectively where the connections are open to ready inspection and repair. 10

CLINTON O. HARRINGTON.
